(57) **CLAIM**

The ornamental design for a translucent plastic sequentially lighted and timed balancing tube, as shown.

DESCRIPTION

FIG. 1 is a perspective view of a translucent plastic sequentially lighted and timed balancing tube showing my new design;

FIG. 2 is a front elevational view thereof;

FIG. 3 is a representative side elevational view thereof;

FIG. 4 is a rear elevational view thereof;

FIG. 5 is a top plan view thereof; and,

FIG. 6 is a bottom plan view thereof.
